CLAIM

The ornamental design for a loudspeaker front face, as shown and described.

DESCRIPTION

FIG. 1 is a front perspective view of a loudspeaker front face showing the new design;

FIG. 2 is another front perspective view thereof;

FIG. 3 is a front elevational view thereof;

FIG. 4 is a rear elevational view thereof;

FIG. 5 is a side elevational view thereof;

FIG. 6 is an opposite side elevational view thereof;

FIG. 7 is a top view thereof; and,

FIG. 8 is a bottom view thereof.

The broken lines in the figures illustrate portions of the design that form no part of the claimed design.
